(57) **CLAIM**

The ornamental design for a flush hose for multiple outboard engines, as shown and described.

DESCRIPTION

FIG. 1 is a front perspective view of a flush hose for multiple outboard engines, showing my new design;

FIG. 2 is a rear perspective view thereof;

FIG. 3 is a top view thereof;

FIG. 4 is a left side view thereof the right side view being a mirror image thereof;

FIG. 5 is a rear view thereof; and,

FIG. 6 is a front view thereof.

The hose is shown broken away with dashed, zig-zag, cut-off lines in the figures to indicate that no specific length is being claimed—it is understood that the interrupted portion of the hose has a uniform shape and appearance through out its length.

The broken line portion of the figure drawings showing a typical usage environment in FIG. 1 is included to show unclaimed subject matter only and forms no part of the claimed design.
